UNITED STATES PATENT OFFICE

JOHN EDGREN, OF THAYNE, WYOMING

AIR-COMPRESSING COUPLING FOR ENGINE CYLINDERS

Application filed June 27, 1928. Serial No. 288,741.

The present invention relates to attachments for internal combustion engines and has for its principal object to provide a coupling adapted for attachment to the cylinder of an engine for connecting the same with a compressed air tank, whereby to utilize the compression of the engine cylinder for compressing a supply of air in said tank.

A further object of the invention is to provide an attachment of this character adapted for fitting in the spark plug opening communicating with the cylinder and also providing a connection for the spark plug so as to permit the firing of the cylinder in the usual manner.

A further object is to provide a cut-off means between the cylinder and the compressed air tank and the spark plug, so that either the tank or the spark plug may be cut off from communication with the cylinder when desired.

An additional object is to provide an attachment of this character of a simple and practical construction, which may be easily and quickly installed in operative position without necessitating any changes or alterations in the construction of the engine, relatively inexpensive to manufacture, and otherwise well adapted for the purpose for which the same is intended.

Other objects and advantages reside in the special construction and combination of the various elements comprising the invention, reference being had to the accompanying drawing, forming a part hereof, and wherein:

Figure 1 is a side elevational view showing the coupling with a spark plug mounted in position therein, and

Figure 2 is a vertical sectional view therethrough.

Referring now to the drawing in detail, the invention comprises a coupling composed of a body portion 5, provided at one end with an externally threaded nipple 6, adapted for threaded insertion in the spark plug opening of the cylinder of an internal combustion engine, and having its opposite end internally threaded for mounting the spark plug 7 in position therein. From one side of

the body 5 is a threaded opening 8 in which is threadedly fitted one end of a feed pipe 9, extending to a compressed air tank. A three way air valve 10 is seated within the body and disposed for rotation upon an axis at 55 right angles to the longitudinal axis of the body, the ends of the valve 10 extending to opposite sides of the body and retained in position therein by a nut 11. One of the nuts also serves to mount an operating lever 60 12 on one end of the valve, said lever extending longitudinally of the body and in spaced parallel relation with respect to the spark plug 7. The upper end of the lever is provided with an angular extension 13 disposed transversely with respect to the spark plug and engageable with the upper portion thereof whereby to provide a stop for the lever and limit the turning movement of the valve in one direction. An operating rod 65 14 is attached at one end to the lever, with its opposite end extending in a direction toward the operator of the engine for control thereby. As clearly illustrated in Figure 2 of the drawing, the passageway 15 formed 70 in the valve, provides a means for controlling communication through the body 5, with either of the feed pipes 9 extending to the compressed air tank, or with the spark plug 7. Accordingly upon the operation of the lever 12, in a predetermined manner, the valve 10 may be moved into a suitable position for permitting communication between the spark plugs and the cylinder of the engine, whereby to enable the firing of the cylinder in the usual manner and when said lever is moved into an opposite position, as shown by the dotted lines in Figure 2, communication between the cylinder and the spark plug will be closed, whereby to prevent 75 the firing of the cylinder and at the same time communication between the feed pipe 9 and the cylinder is opened and in this manner to feed the air compressed in the cylinder to the compressed air tank. It will thus be 80 apparent that the cylinder of the engine may be utilized to feed air under pressure to a compressed air tank and utilize for any useful purpose, such as for instance the connection with a spraying apparatus mounted on 85 90 95 100

a vehicle, together with the engine for agricultural or horticultural purposes.

It is obvious that the invention is susceptible of various changes and modifications, without departing from the spirit or scope of the invention or sacrificing any of its advantages, and I accordingly claim all such forms of the device to which I am entitled.

Having thus described my invention, what I claim as new is:

- 10 1. An attachment for engine cylinders comprising a hollow body having a threaded nipple formed on one end adapted for threaded engagement with the spark plug opening of the cylinder and having its opposite end arranged for threadably receiving the spark plug whereby to provide communication between the cylinder and the spark plug through the body, a feed pipe extending laterally from one side of the body, and a valve operatively arranged in the body and adapted for selectively controlling communication with the cylinder of either the spark plug or the feed pipe.
- 15 2. An attachment for engine cylinders comprising a hollow body having a threaded nipple formed on one end adapted for threaded engagement with the spark plug opening of the cylinder and having its opposite end arranged for threadably receiving the spark plug whereby to provide communication between the cylinder and the spark plug through the body, a feed pipe extending laterally from one side of the body, a valve operatively arranged in the body and positioned between the spark plug and the cylinder attached end of the body for selectively controlling communication between either the spark plug or said feed pipe with the cylinder, said valve having one end extending outwardly of the body, and an operating lever attached thereto.
- 20 3. An attachment for engine cylinders comprising a hollow body having a threaded nipple formed on one end adapted for threaded engagement with the spark plug opening of the cylinder and having its opposite end arranged for threadably receiving the spark plug whereby to provide communication between the cylinder and the spark plug through the body, a feed pipe extending laterally from one side of the body, and a valve operatively arranged in the body and adapted for selectively controlling communication with either the spark plug or said feed pipe with the cylinder, said valve having one end extending outwardly of the body, an operating lever attached thereto and an extension formed on said lever and engageable with a stationary part of the device whereby to form a stop for indicating one position of the valve.

In testimony whereof I affix my signature.
JOHN EDGREN.
